DESIGN FOR A COMPACT HOLDER

Elsa Schiaparelli, Paris, France, assignor to Societe des Parfums Schiaparelli (Societe Anonyme), Paris, France, a corporation of France

Application June 21, 1939, Serial No. 85,603

Term of patent 14 years

To all whom it may concern:

Be it known that I, Elsa Schiaparelli, a citizen of the Republic of France, residing at Paris, France, have invented a new, original, and ornamental Design for a Compact Holder, of which the following is a specification, reference being had to the accompanying drawing, forming part thereof.

In the drawing

Fig. 1 is a perspective view of a compact holder showing my new design in closed position;

Fig. 2 is a similar view but in open position; and

Fig. 3 is a rear elevational view thereof.

I claim:

The ornamental design for a compact holder, as shown.

ELSA SCHIAPARELLI.
